HAND HELD FLUID DISPENSER AND BRUSH FOR
CLEANING UPHOLSTERY OR THE LIKEKenneth E. Gibbs, Wyoming, Mich., assignor to Bissell
Inc., Grand Rapids, Mich.

Filed May 5, 1971, Ser. No. 140,648

Term of patent 14 years

Int. Cl. D4—01

U.S. Cl. D4—7

Fig. 1

Fig. 2

Fig. 3

Fig. 4

Fig. 5

Fig. 6

FIG. 1 is a perspective view of a hand held fluid dispenser and brush for cleaning upholstery or the like which embodies my new design;

FIG. 2 is a right side elevation thereof, the opposite side being a mirror image;

FIG. 3 is a front elevation thereof;

FIG. 4 is a rear elevation thereof;

FIG. 5 is a top plan view thereof; and

FIG. 6 is a bottom plan view thereof.

I claim:

The ornamental design for a hand held fluid dispenser and brush for cleaning upholstery or the like, substantially as shown and described.
